UNITED STATES PATENT OFFICE.

WILLIAM H. MILLSPAUGH, OF SANDUSKY, OHIO.

PAPER-MAKING MACHINE.

Application filed May 27, 1925, Serial No. 33,219. Renewed November 30, 1927.

This invention aims to provide an improved wet machine for use in making paper in a continuous sheet, more particularly by a vacuum forming process.

5 The invention will be understood by reference to an illustrative embodiment thereof shown in the annexed drawings, in which:

Fig. 1 is a plan view of one practicable construction embodying the invention.

10 Fig. 2 is a side elevation thereof, with the suction roll in cross section.

Fig. 3 is a larger sectional elevation taken on the line 3—3 of Fig. 1, looking in the direction of the arrow.

15 Fig. 4 is a sectional elevation taken on the line 4—4 of Fig. 3, looking in the direction of the arrow.

In the drawings, 5 denotes the rotating perforated cylinder of a suction roll of any 20 appropriate construction for maintaining vacuum action on a desired cylindric area. The direction of rotation is indicated by the arrow in Figs. 2 and 3. The cylinder bearings and driving gears for rotating it are 25 not shown, such features being well known in the suction roll art.

An endless strainer medium 6, preferably of wire cloth such as the ordinary Fourdrinier making wire, is shown entrained upon 30 and driven by the suction roll, providing a paper forming surface on the vacuum-affected area of the roll and also serving to convey the sheet from the roll for delivery to a succeeding section of the paper machine, 35 for instance to a press section. The delivery end of the wire cloth and means for transferring the paper sheet therefrom are not shown.

A body of liquid stock for paper formation 40 is shown in Fig. 3 bearing on a segment of the cylindrical forming surface provided by the wire-covered portion of the suction roll, i. e. by the wire cloth traveling on the roll. Means for holding such liquid body on the 45 suction roll is represented by the open-ended vat 7. It will be understood that the liquid stock is continuously supplied to and maintained at a substantially constant level in the vat or receptacle by appropriate means.

50 In the cylinder opposite the liquid receptacle there is shown a vacuum chamber 8 which in this instance is provided by a stationary suction box, the open side of which bears against the interior surface of the cylinder. There is also shown a supplemental vacuum chamber 11 which in this in-

stance is provided as a separate compartment of the same box structure. The suction box packings in contact with the interior surface of the cylinder are indicated at 10. The 60 chamber 8 communicates by the pipe 9 with suitable apparatus (not shown) for maintaining in said chamber a substantially uniform vacuum of appropriate degree to effect vacuum-induced formation of a paper sheet 65 on the wire cloth traversing the arc of contact with the liquid stock, while drawing off the large volumes of water from the stock from which the paper forms. The chamber 11 likewise communicates by the pipe 12 with 70 a suitable vacuum pump for maintenance of such vacuum as may be required in said chamber.

As the cylinder revolves the wet paper sheet forms under vacuum action on the 75 forming surface as it traverses the arc of contact with the liquid stock or while exposed to the vacuum chamber 8. Said chamber 8 is shown extended a substantial distance above the level of the liquid in the receptacle 80 7, whereby the wet sheet emerging from the liquid is held intact as formed and the sheet undergoes drainage by the continued action of the forming vacuum. Further drainage and compacting of the paper sheet takes 85 place as the sheet is carried over the supplemental vacuum chamber 11. The vacuum in said supplemental chamber 11 may be regulated or adjusted to force substantially uniformly through the sheet such quantities of air as to carry off or expel sufficient moisture to bring the sheet to a desired low moisture condition. Ordinarily in making a single sheet of paper a comparatively high vacuum 90 would be maintained in the chamber 11 to 95 force the air in large volumes substantially uniformly through the sheet, so as to reduce the sheet to the minimum moisture content permissible by this method and bring it to condition for effectively withstanding a succeeding pressing or smoothing operation. According to various conditions, the amount of moisture reduction may be varied. For instance, the vacuum in the chamber 11 may be 100 adjusted to bring the sheets substantially to a predetermined moisture content most advantageous for bonding with another sheet or other sheets being simultaneously made on another suction roll or other rolls in the same machine.

The vat 7 is shown constructed with laterally-adjustable members comprising vertical

plates 13 constituting side wall portions of the vat and inwardly extending bottom members 14 constituting portions of the bottom of the vat. Said adjustable members are shown 5 as angle structures which in addition to the side plates 13 and bottom plates 14 are constructed with outwardly extending bottom plate extensions 13^a and outwardly extending vertical plates 13^b. The bottom plates 14 10 may overlap as shown in Figs. 3 and 4, thereby providing for adjustment of the vat bottom with adjustment of the side walls. The overlapping bottom plates 14 are shown having their edges adjacent the cylinder grooved 15 or rabbeted for accommodation of correspondingly overlapping rubber strips 32 (Fig. 3) which lap the cylinder to aid in preventing leakage of pulp liquid at the bottom of the vat.

20 The said adjustable vat members may be slidably supported on horizontal beams 15 below the vat bottom at either side thereof, and the overlapping bottom plates 14 may rest on an intermediate beam 16 as shown in said figures. Means for adjusting the said adjustable members inwardly and outwardly are represented by the screws 17 which in this instance are carried by said members, being 25 non-rotatably secured in brackets 18 on the outer bottom extensions 13^a of said members. Said screws are threaded through the internally-threaded hubs or nut portions of hand wheels 19, the hubs of which are journaled and retained against endwise movement in 30 bearings carried by the brackets 20. Thus by operating the hand wheels the screws will move the said adjustable members inwardly or outwardly to control the position of the side-wall portions 13 according to the width 35 of paper sheet to be made. The outward bottom extensions 13^a of said adjustable members are shown secured to subjacent supporting beams 15 by bolts 21 passing through slots in said extensions to permit desired adjustments 40 (Fig. 1). The outer vertical extensions or plates 13^b, which fit against coacting face plates provided by the brackets 23, may be 45 adjustably secured by appropriate means represented by clamps 22.

50 The vertical side plates 13 of the adjustable vat members are shown having concave edges spaced from the forming surface in the cylinder. To confine the liquid stock laterally on 55 said surface, deckles 24 traveling on or with the cylinder cooperate with the said side plates to close the spaces between them and the forming surface. These deckles are shown as endless thick bands of flexible material appropriate for the purpose, for instance rubber or 60 the like. The deckles are shown traveling around pulleys 25 and 26, arranged respectively above and below the vat, said pulleys being so disposed as to entrain the deckles on the forming surface of the cylinder through 65 an ample arc to confine the liquid. The

deckles may be entrained upon the cylinder under sufficient tension to be driven by the cylinder, or they may be independently driven. The return runs of the deckles are shown passing through inclined guide-passages 27 constructed in this instance on the inner sides of the side plates 13 of the adjustable vat members.

The upper deckle pulleys 25 are shown mounted on a shaft 28 journaled in bracket 75 members 29 secured to the vat walls. The lower deckle pulleys 26 are shown mounted on a shaft 30 the bearings for which are adjustably secured to brackets 31 for increasing or decreasing the tension on the deckles. 80 Both sets of pulleys may slide freely on their respective shafts to permit lateral adjustment of the deckles with the lateral adjustment of the vat side wall portions or plates 13. Preferably the deckle pulleys are splined to 85 the shafts, particularly if driven otherwise than from the cylinder through the contacting deckle bands themselves.

With the construction described, the paper sheet forms on the wire-cloth covered portion 90 of the cylinder or suction roll, the sheet forming with edges determined by the inner flat faces of the traveling deckles; and said deckles are co-adjustable with the adjustable vat side and bottom portions 13 and 14, for 95 regulating as desired the width of the liquid in contact with the forming surface, according to the width of the sheet of paper to be made. It will be understood that the width of the vacuum chambers in the cylinder 100 should be correspondingly adjusted, which adjustment is accomplished by employing suction boxes equipped with adjustable ends or heads, not herein specifically illustrated as the same has been illustrated in Patent No. 105 1,025,822 and in prior copending applications of the present inventor.

It will be understood that the present invention is not limited to the particular embodiment thereof herein shown and described.

In my prior and now pending applications Ser. Nos. 610,538 and 610,539, filed January 3, 1923, I claim the process or processes of 115 wet sheet formation herein disclosed, and also broadly claim a machine or apparatus of the kind herein disclosed; this application being for subject-matter not specifically disclosed in said prior applications but subordinate to the broader inventions therein 120 claimed. In my prior application filed May 11, 1925, Ser. No. 29,600, I claim a method and machine involving the conditioning of the wet sheet as hereinbefore stated for bonding with another such sheet.

125 What I claim herein is:

1. A paper-making machine comprising, in combination, means providing a continuously moving cylindric forming surface; means for forming a continuous paper sheet 130

on said surface under action of vacuum exerted upon liquid stock bearing upon said surface; and means for laterally supporting said liquid stock including vat walls spaced 5 from said surface and endless deckle bands traveling on said surface and cooperating with said walls to close the spaces between said walls and surface.

2. A paper-making machine comprising, 10 in combination, means providing a continuously moving cylindric forming surface; means for forming a continuous paper sheet on said surface under action of vacuum exerted upon liquid stock bearing upon said 15 surface; and means for laterally supporting said liquid stock including vat walls spaced from said surface and traveling means cooperating with said walls to close the spaces between said walls and surface.

20 3. A paper-making machine comprising, in combination, a sheet-forming suction roll; endless deckle bands entrained upon and traveling with the forming surface of the suction roll; and a vat having lateral walls 25 engaged by and cooperating with said deckle bands for holding liquid stock on the forming surface of the suction roll.

4. A paper-making machine comprising, 30 in combination, a sheet-forming suction roll and cooperating liquid holding means including laterally adjustable side walls and endless deckle bands coadjustable with said side walls, said deckle bands traveling beside said walls on the sheet-forming surface 35 of said suction roll.

5. A paper-making machine comprising, 40 in combination, a sheet-forming suction roll; endless deckle bands entrained upon and traveling with the suction roll; and an open-ended receptacle for liquid stock having laterally adjustable side wall and overlapping bottom members; said bottom members having overlapping flexible strips bearing on the forming surface of the suction roll between 45 said deckle bands; and said deckle bands coadjustable with said side wall members.

6. A paper-making machine comprising, 50 in combination, a sheet-forming suction roll; endless deckle bands entrained upon and traveling on the sheet forming surface of the suction-roll; and a receptacle for liquid stock having side walls cooperating with said deckle bands and having a flexible bottom strip bearing on the forming surface between 55 said deckle bands.

7. A paper making machine comprising, 60 in combination, a suction roll comprising a rotating perforated cylinder having a sheet-forming surface and equipped to apply vacuum action on a portion of said surface; and means for applying liquid stock on an area of said surface subjected to vacuum action, including traveling deckles between which the liquid is confined on said area.

65 8. A paper-making machine comprising,

in combination, an endless traveling strainer medium; a suction roll around which said endless strainer medium is trained; endless deckle bands traveling on the cylindric forming surface provided by the portion of the strainer medium entrained upon the suction roll; and means for applying liquid stock to said portion of the strainer medium between said deckle bands. 70

9. A paper-making machine comprising, 75 in combination, an endless traveling strainer medium; a suction roll around which said endless strainer medium is trained; endless deckle bands traveling on the cylindric forming surface provided by the portion of the strainer medium entrained upon the suction roll; and laterally-extensible means cooperating with said deckle bands for holding liquid stock on the suction roll between said deckle bands; said deckle bands being co-adjustable with said last named means. 80

10. A paper-making machine comprising, 90 in combination, means including a suction roll providing a cylindric sheet-forming surface; and cooperating means including traveling deckle bands for holding liquid stock on a segment of said cylinder forming surface above the lower side of the suction roll, said means adjustable to control the width of the liquid column bearing on the suction 95 roll.

11. A paper-making machine comprising, 100 in combination, a suction-roll; cooperating liquid stock holding means including deckle bands on the suction roll; and means associated with the suction roll for exerting vacuum action on the sheet formed on said roll after the sheet leaves the sheet-forming area.

12. In a paper-making machine, the combination with a cylindric forming surface 105 of cooperating liquid stock holding means including laterally-adjustable side walls and bottom members, said bottom members overlapping and having overlapping flexible strips bearing on the forming surface. 110

13. In a paper-making machine, the combination with a cylindric forming surface of cooperating liquid stock holding means including laterally adjustable side wall members and deckle bands co-adjustable therewith. 115

14. In a paper-making machine, the combination with a cylindric forming surface of a cooperating receptacle for holding liquid stock on said surface; endless deckle 120 bands traveling on said surface beside the side walls of said receptacle; and deckle pulleys therefor arranged above and below said receptacle.

15. In a paper-making machine, the combination with a cylindric forming surface of a cooperating receptacle for holding liquid stock on said surface; endless deckle bands traveling on said surface beside the side walls of said receptacle; and guide-ways 130

for the return runs of said deckle bands, said guideways being unitary with the side walls of said receptacle.

16. In a paper-making machine, the combination with a cylindric forming surface of a cooperating receptacle for holding liquid stock on said surface; endless deckle bands traveling on said surface beside the side walls of said receptacle; a side wall member of the receptacle being laterally adjustable; and the corresponding deckle band being so associated therewith as to move laterally with said side wall member.

17. In a machine of the class described,

the combination with a cylindric forming surface, of a laterally adjustable vat; endless deckle bands traveling on said surface beside the side walls of the vat; deckle pulleys; and shafts therefor; a deckle pulley being slideable on its shaft to permit deckle adjustment with vat adjustment.

18. In a machine of the class described, the combination with a cylindric forming surface of a laterally adjustable vat; deckles co-adjustable with the vat; and operating means for adjusting the vat and deckles therewith.

In testimony whereof I affix my signature.

WILLIAM H. MILLSPAUGH.
